UNITED STATES PATENT OFFICE.

ISIDOR DEUTSCH, OF MONTREAL, CANADA, ASSIGNOR TO ELECTRIC AND TRAIN LIGHTING SYNDICATE, LIMITED, OF MONTREAL, CANADA, A CORPORATION OF CANADA.

BRUSH-HOLDER FOR ELECTRIC GENERATORS.

SPECIFICATION forming part of Letters Patent No. 774,163, dated November 8, 1904.

Application filed May 14, 1903. Renewed March 25, 1904. Serial No. 200,031. (No model.)

To all whom it may concern:

Be it known that I, ISIDOR DEUTSCH, a citizen of the United States of America, residing at Montreal, in the district of Montreal, Province of Quebec, Canada, have invented certain new and useful Improvements in Brush-Holders for Electric Generators, of which the following is a specification.

My invention relates to improvements in brush-holders for electric generators; and the object of the invention is to devise a holder which will not allow the brush to stick in the holder and whereby the brushes will be in a proper commutating position no matter how much they may wear; and it consists, essentially, of brush-holding arms moving parallel to the commutating plane and bearings therefor disposed substantially at right angles to the axis of the commutator, the various parts being constructed in detail as hereinafter more particularly described.

Figure 1 is a side elevation of a dynamo, showing a back view of my brush-holders. Fig. 2 is an end elevation of a dynamo from the commutator end, showing my brush-holders in position. Fig. 3 is a detail of the parallel holding-arms. Fig. 4 is a detail of the fingers which engage the back of the brushes. Fig. 5 is a detail of the supporting-plate of the bearing. Fig. 6 is a detail of a box designed to contain a brush.

Like letters of reference indicate corresponding parts in each figure.

a represents the brushes of the dynamo, preferably contained in the boxes *b*, having the orifices *c*.

d represents bearings forming parts of the plates *e*, which are securely bolted to the dynamo-frame in proximity to the commutator *f* and substantially at right angles to the axis of the commutator.

g represents parallel arms swinging inwardly parallel with the commutating-plane from the bearings *d*.

45 *h* represents orifices in the parallel arms, and *i* represents lateral projections forming part of the arms *g*.

The boxes *b* having the brushes *a* therein

are inserted between the parallel arms *g* and the orifices *c* in the boxes brought in alignment with the orifices *h*. The pins *j* are then inserted through the orifices *h* and *c* and at the same time through holes in the brushes *a*. The brushes now are held firmly in the boxes *b*, which swing pivotally to and from the commutator in between the arms *g*.

The projections *i* from the arms *g* are designed to steady the boxes *b* and keep the same in a parallel position.

k represents rods projecting from the plates *e* below the bearings *d* and parallel with the commutator *f*.

l represents hollow tubes having the slots *m* cut therein intermediate of their length.

n represents fingers securely attached at 65 each of the ends of the hollow tubes.

The hollow tubes *l* slide over the rods *k*, and the pins *o* are inserted in the rods *k* through the slots *m* in the tubes *l*.

p represents spiral springs encircling the tubes *l* and held in the center by the pins *o* and at the ends by the fingers *n*, to which they exert an inward pressure. The fingers *n* are designed to press on the back of the brushes *a* to hold the same against the commutator *f*.

75 The utility of my brush-holder will be readily seen from the description of the parts, as the parallel arms holding the brush-holders in the boxes swing inwardly parallelly with the commutating-plane, and consequently 80 keep the brushes always in a perfectly-parallel position. There is no possibility of the brushes sagging down or in any way becoming angularly displaced—that is to say, as the carbon brush wears away the spring-fingers 85

press the brush against the commutator in such a manner that the angular displacement between the two brushes with respect to the commutator is always the same. The spring-fingers are securely attached in each case to 90 the tubes, so that they must both move exactly the same, and therefore the brush will always be square with the commutator, and the brushes in relation to one another will always be in the proper commutating position, 95 which is particularly essential in dynamos

which generate by rotation in either direction. The plates *e* must of course be properly insulated from the frame of the dynamo.

What I claim as my invention is--

5 1. In a brush-holder, the combination with the commutator, of a pair of brush-holding arms at the side of the commutator and moving parallel to the commutating-plane, a pivot-bearing for said pair of arms disposed substantially at right angles to the axis of the commutator and means for holding a brush between said pair of arms, substantially as described.

15 2. In a brush-holder, the combination with the commutator of a pair of connected brush-holding arms at the side of the commutator, and moving parallel to the commutating-plane, a bearing therefor disposed substantially at right angles to the axis of the commutator and a carbon-brush-holding box pivotally supported between the pair of arms, substantially as described.

25 3. In a brush-holder, the combination with the commutator, of brush-holding arms moving parallel to the commutating-plane, and a bearing therefor disposed substantially at right angles to the axis of the commutator, a carbon brush carried in the arms, and spring-held fingers engaging the back of the brush to hold the same against the commutator, as and for the purpose specified.

35 4. In a brush-holder, the combination with the commutator, of brush-holding arms moving parallel to the commutating-plane, and a bearing therefor disposed substantially at right angles to the axis of the commutator, a carbon brush carried in the arms and thereto attached, and a plurality of fingers spring-held and journaled on a rod located parallel 40 with the commutator, as and for the purpose specified.

45 5. In a brush-holder, the combination with the commutator, of brush-holding arms moving parallel to the commutating-plane, a bearing therefor disposed substantially at right angles to the axis of the commutator, and projecting from a suitably-insulated support in proximity to the said commutator, a box piv-

otally secured between the said arms, a carbon brush within the box and spring-held fingers secured to a tube journaled on a rod extending from the insulated supports and parallel with the commutator, as and for the purpose specified.

55 6. In a brush-holder, the combination with the commutator, of brush-holding arms moving parallel to the commutating-plane, a bearing therefor disposed substantially at right angles to the axis of the commutator, and projecting from a suitably-insulated support in 60 proximity to the said commutator, a box pivotally secured between the said arms, a brush in said box, a rod extending from the insulated support and having a projecting pin intermediate of its length, fingers secured to a 65 tube slotted centrally and turning on the said rod and a spiral spring encircling the tube and held by a projecting pin and exerting a pressure on the fingers at their outer ends, as and for the purpose specified.

70 7. In a device of the class described, the combination with the commutator of a pair of parallel arms having orifices therethrough, and inwardly-turning ends and hinged at right angles to the axis of the commutator from a 75 suitably-insulated support on the dynamo-frame, and a carbon brush supported by said pair of arms as and for the purpose specified.

80 8. In a device of the class described, in combination, a commutator, a box having orifices therethrough, a carbon brush designed to fit into the said box, a pin inserted through said orifices and brush, parallel arms pivotally supported from the dynamo-frame and moving parallel with the commutating-plane, and a 85 pair of parallel fingers spring-held to the back of the box and journaled parallel with the commutator, as and for the purpose specified.

Signed at Montreal, in the district of Montreal, in the Province of Quebec, Canada, this 90 11th day of May, 1903.

ISIDOR DEUTSCH.
